ICE CUBING MACHINE

James F. Turner and Christian P. Breidenbaugh,
Baltimore, Md., assignors to Flynn & Emrich
Company, Baltimore, Md., a corporation of
Maryland

Application January 31, 1939, Serial No. 253,736

12 Claims. (Cl. 143—38)

This invention relates to a machine for cutting blocks, from relatively large bodies of material and is particularly adapted for cutting cubes of ice.

It is the object of the present invention to provide an ice cubing machine which is not only highly efficient in its operation but adapted to be constructed at a relatively small cost so that it can be sold at a price suitable to hotels, restaurants, and those who consume cubes in relatively small quantities.

This machine, like the previous machines comprises a single set of scoring saws and a single cut off saw, the cakes being reciprocated on a single predetermined rectilinear path and turned at each end of the path. The scoring saws are intermediate of said path, the cut off saw being at one end of said path and the loading station at the other end of the path.

While the direction of the path of reciprocation of the cakes in the machine shown is substantially horizontal, a degree of inclination to the horizontal would not be regarded as harmful. Relatively important features of the machine of the invention are that the cake of ice or other body being cut, though it is controlled and turned by means of cage or container, referred to herein as a hopper, which encloses it laterally, is supported on a table, the hopper being open downwardly for this purpose and the hopper is turned at the ends of its stroke about an axis which extends upwardly being substantially normal to the table which except as to certain phases of the invention is essentially inclined to the horizontal in a direction transverse to the path of reciprocation.

In the present machine the saw guard serves, in addition to its function in the previous machines, to support the cake after the cut off, for this, and other purposes, it is an important feature of the machine, the hopper is mounted eccentrically or off center as to the axis about which it rotates so that when it is turned after the cut off operation, the cake is thrown off center and rests on the guard at the side of the saw instead of resting on the saw. This makes it possible to cut any size or shape of cake so long as it will enter the ice container or hopper.

It is also an important novel feature of the invention that the turning of the hopper is so related to the inclination of the axis about which it turns that one corner of the hopper, preferably having the greatest radius of the hopper about said axis, is always in registration with the low side of the table. The cake is placed in contact with the converging sides of the hopper at the corner and remains positioned by these converging sides, during the entire cutting operation. Preferably the handle by which the hopper is operated extends outwardly in the direction of

a diagonal of the hopper through this corner.

The cake is further clamped and held against yielding by a clamp which has an automatic take-up which causes the clamp to follow the cake

5 downwardly as it diminishes in height due to consumption of its lower end by cutting so that clamp operates until the cake is consumed. This automatic clamp serves to steady the cake and hold it in a fixed position relatively to the hopper as it passes in cutting relation with the saws and at all times. Without it the ice cake would have a tendency to yield laterally or upwardly due to the action of the scoring saws resulting in injury to the saws or insufficient and irregular scoring as to depth. It is also of interest that the ice container or hopper which is supported on a reciprocating carrier is so mounted on the carrier that it turns about a single bearing at its top, the elaborate and expensive construction of

10 the corresponding portions of the previous machines being dispensed with, thus reducing the friction to a minimum and making it easy to operate the machine manually in the manner hereinafter described, and greatly simplifying and correspondingly reducing the cost of the present machine.

This suspension of the hopper by a single bearing at the top is important in its relation to the inclination of the axis of the hopper in a plane transverse to the path, in that it provides in a convenient manner for the eccentricity of the hopper and thereby for holding the cake at all times in a satisfactory cutting position throughout its cycle from the time the cake is loaded 20 until the cubing operation is completed, the cake or supply of ice in the hopper being exhausted.

While this machine is designed with a view to the operation of the carriage by hand, it may be otherwise operated, and the details of the hand operation are regarded as in themselves constituting an important feature of the invention.

As already pointed out, the hopper is turned at each end of the path and the handle is so arranged that the hopper is turned by the natural swing of the handle in reversing the stroke. Stops are provided for limiting the motion of the hopper as it turns at each end of the path and an additional stop is provided in the form of a roller which engages a track intermediate of the path, i. e. extending substantially from one turning position of the hopper to the other. The track is engaged by this roller after each turning operation thus preventing turning or partial turning of the carriage intermediately of the stroke and particularly in the portion of the path occupied by the scoring saws so as to prevent deflection of the cake during scoring and consequent breaking of the saws or other undesired operations or effects.

With these and other objects in view we have illustrated in the drawings a preferred form of machine embodying the invention, considerable variations in details of construction being contemplated.

In the drawings:

Figure 1 is an end elevation of the machine, viewed from the loading end.

Figure 2 is an elevation of the machine looking from the right in Figure 1, the plane of the illustration being parallel to the axis of the hopper as indicated by the line 2—2 in Figure 1, the arrows showing the direction in which the observer looks at the machine in Figure 2.

Figure 3 is a section on the line 3—3 in Figure 2.

Figure 4 is a section on the line 4—4 in Figure 2.

Figure 5 is a sectional plan on the line 5—5 in Figure 2.

Figure 6 is a sectional plan on the line 6—6 in Figure 2. Both Figures 5 and 6 are taken looking downwardly.

Figure 7 is a fragmentary plan of the cut-off saw and guard, the table beyond the guard being broken away and the super structure, i. e., the portions over the saw and guard being removed.

Figure 8 is a fragmentary top plan view of the machine showing the carriage and hopper over the cut-off saw after rotating the carriage following the cut-off, the carriage being ready for the return stroke to the left toward the scoring saws as indicated by direction arrows, the left hand end of the machine beyond the scoring saws being broken away.

Figure 9 is a section on the line 9—9 in Figure 5, showing a fragment of the cut-off saw in the operation of cutting off the cubes after scoring of the cake, the shute and table being also shown fragmentarily as well as the lower portion of the walls of the hopper.

Figure 10 is a section on the line 10—10 in Figure 8, it being assumed that the hopper handle is in mid-position for the purpose of illustrating the latches in connection with the automatic take up clamp.

Figure 11 is a fragmentary elevation of the upper portion of the structure shown in Figure 10.

Figure 12 is a horizontal section on the line 12—12 in Figure 11, looking downwardly.

Referring to the drawings by numerals, each of which is used to indicate the same or similar parts in the different figures, the machine as shown comprises end frames 1 and 2 which are connected by a table 3 and longitudinal top structure 4, the machine being closed by side plates 5 and 6. It is of interest that the table 3 is inclined transversely to the direction of the length of the machine which is the direction of the path of reciprocation of the cake. The angle of the inclination of the table in the machine shown herewith is approximately 15 to 20 degrees from the horizontal, the exact inclination not being important.

The loading end of the machine is open at 7 for the admission of the cake in loading, the opposite end being preferably closed to prevent contact with the cut-off saw. The enclosing of the sides of the machine by protective plates 5 and 6 as aforesaid, is for the purpose of protecting the operator, all chances for injury being eliminated.

These side and end walls also confine the

snow and fine particles of ice thrown off by the scoring and cut-off saw members. At the loading end 7 the machine as shown is provided with a projecting shelf 8 in line with the inclined supporting plane of the table 3, the shelf supporting surface being similarly inclined, and this shelf as shown is provided with an upright side 9 to prevent the cake from sliding or slipping from the shelf. The purpose of the shelf is to support the cakes as introduced, and to be introduced.

The shelf as shown is provided with a pivoted shield 10, the purpose of which is to prevent the snow or ice dust from the scoring saws from being projected outwardly from the machine. A large proportion of the snow dust from the cut-off saw being discharged through the snow shute 11.

The shield 10 as shown projects laterally across the shelf 8 and is pivotally mounted at 12 and has a counter-balance and stop at 14. In operation, the shield is turned downwardly into the plane of the shelf when the cake indicated 15 is advanced over the shelf as the cake passes into the hopper, and the shelf is slotted at 8' for this purpose. The shield is returned to upright position as shown in dotted lines by the action of the counter weight 14. The shield forms a rigid part of the shelf surface when the same has been moved downwardly as shown, due to the counter balance stop 14', stopping the downward swing of the shield at the supporting plane of the shelf 8.

The scoring saws 20 consist of a single gang of saws suitably spaced to give cubes of the desired dimensions and these scoring saws are mounted on a single mandrel 21 which is secured to a shaft 22. This shaft 22 rotates in bearings 24 which are stationary being secured to suitable brackets 25 at the sides of the table. The mandrel 21 and shaft 22 are parallel to the supporting plane of the table 3 at right angles to the length of the table, and path of reciprocation of the cake, i. e. they extend transversely of the table and are similarly inclined, i. e. at an angle of approximately 15 to 20 degrees to the horizontal or any suitable variation thereof. The mandrel 21 and shaft 22 are preferably positioned directly beneath the table as shown, the scoring saws 20 projecting upwardly through the table by way of slots 20' into scoring relation with a cake on the table or passing along the table.

The cut-off saw indicated by reference character 26 is parallel to the table 3 and mounted on the upper end of the shaft of an electric motor 27 which is supported on a suitable bracket 28 on the frame of the machine as best shown in Figure 4. The axis of the motor is inclined at an angle of 15 or 20 degrees to the vertical being at right angles to the table which is similarly inclined to the horizontal. The cut-off saw 26 being mounted on the motor shaft is parallel to the table 3 and it is also spaced above the table by a predetermined distance equal to the height or depth of the cubes being cut. The cut-off saw is mounted in an opening 32 in the saw guard 29 as best shown in Figures 4, 5, 7 and 9.

This cut-off saw guard 29 in the form of the invention shown, is formed integrally with the table 3 which is deflected upwardly at 30 as shown in Figures 2 and 7, placing the guard 29 in a plane parallel to the table 3, and spaced above the table sufficiently to give the desired

height to the cubes. The guard 29 is apertured at 31, providing a circular opening a little larger than the saw 26, the guard and the inclined portion 30 are cut away in the direction of the path of the cake, i. e. in a direction facing toward the scoring saws 20. Thus providing an opening 32 for the admission of the scored cake for and in the cut-off operation. The opening 32 is of approximately the width of the largest cake to be admitted which corresponds to the short or the narrow dimension of the hopper hereinafter described.

Figure 7 shows the saw guard 29 cut away at 33 and a plate 34 covering the opening. This is a relatively thin plate, the cut away portion corresponds to the opening 33 in Figure 4, where the ice dust from the cut-off saw is discharged. The reason for the cutaway and the thin plate, is to facilitate the discharge of the dust and to prevent it from accumulating in the vicinity of the cut-off saw 26. The scoring saws 20 and particularly the shaft 22 and the mandrel 21 which carries the same, are driven by a belt 35 which drives a pulley 36 on the shaft 22 and this belt is driven from a pulley 37 on the shaft of the motor 27, the belt 35 being deflected to the plane of the pulley 36, by means of idler pulleys 38.

The cake of ice to be cut is carried back and forth along the table 3 and presented successively to the scoring saws 20 and the cut-off saw 26 by means of the hopper or ice container 40 which is pivotally mounted on and suspended from a carrier 41, the carrier and hopper together composing the complete carriage 42. The carrier 41 comprises a base 43, which base 43 is provided with four rollers 44 which are mounted in pairs on two axes parallel to the transverse lines of the table, i. e., parallel to the axis of the scoring saws, each roller has a frusto conical portion 45 and a disc like flange 45'. There are two of the rollers 44 on each side of the carrier, and the rollers run in horizontal tracks 47.

Each track is shown in the form of a channel iron, having its flanges 47' turned inwardly. In the form shown each pair of rollers 44 is mounted on one of two shafts 48 and the shafts 48 turn in elongated bosses 49 which extend across the top of the machine from one of each pair of rollers to the other. The said elongated bosses 49 are each provided with roller bearings 49' at their ends as shown. The spacing of rollers 44 and tracks 47 corresponds to the width of the table and of the hopper, the latter to be further described. The shafts 48, the axes of which are the axes of rollers 44 are parallel to the transverse inclination of the table 3, or preferably so, it being understood that the details described and presented herewith are the preferred details, however it is further understood that these details are subject to considerable variation without departure from the spirit of the invention.

The carrier is also provided with a roller 50 which is mounted to rotate about an axis parallel to the axis of the motor 27 and at right angles to the axis of the scoring saws and the plane of the cake supporting surface of the table 3. The carrier 41 as aforesaid supports a hopper 40 which depends therefrom and is pivotally mounted thereon in a manner to be hereinafter described. The roller 50 is carried and positioned on the top of the hopper 40 as shown and may be termed a stop and guide roller which cooperates with a track 51 which extends in a hori-

zontal direction parallel to the path of the hopper and carrier structure and being limited to the center portion of the machine, and particularly in the vicinity of the scoring saws as best shown in Figure 2. This roller 50 engages the track or plate 51 as the hopper and cake approach the scoring saws and continues in engagement therewith until the cake carried by the hopper has passed out of scoring engagement with the said scoring saws. This stop and guide roller 50 acts in a cooperative manner with hopper stops indicated at 54 and 55, located on the top surface of the hopper structure 40 and serves to prevent any deflection of the cake and particularly of the hopper during scoring, deflection of the hopper and hence of the cake being regarded as tending to break the scoring saws or produce irregular and misaligned scoring, and to otherwise interfere with the desired operation of the machine. The roller 50 is shown in contact with the track 51 shown in broken lines in Figure 8, and the roller is also shown in similar engagement in Figure 3.

Having further reference to Figures 4 and 8, 25 the hopper stop, i. e. the structural elements used to limit the rotative movement of the hopper 40 to substantially 90°, comprise a depending rib 52 on the carrier 43 and upright posts or other suitable stops 54 and 55 on the top of the hopper 40. The roller 50 and the track 51 cooperate with both of these stops 54 and 55 when they are respectively in contact with the rib 52, and it may be further said that each of these stops serves to hold the carriage in one or the other of the two operative positions. These positions may be distinguished as the respective positions for scoring in two directions at right angles to each other, and it may be further said that the stop 55 engages and cooperates with the rib 52 during the cut-off operation.

The manner of mounting the hopper 40 on the base 43 of the carrier 41 will now be further considered.

The hopper 40 includes an upper or top portion 40' having a cap 57 which is shown in section in Figure 10, this cap 57 and top portion 40' has depending flanges 58, as shown in Figure 1, to which the sides 59 of the hopper 40 are secured, the hopper being open at the bottom and at one side, the latter for the admission of the cake; this opening as indicated at 60 in Figure 1 is partially closed to retain the cake by means of a gate 61 which is hinged at one side at 61' and fastened at the other end by a hook 61'' which engages the pin 61''' or other suitable engaging and releasing means.

Having particular reference to Figures 10, 11, and 12, the cap or top portion 57 of the hopper is provided at its center with an integral upright tubular member 62. The axis of which is parallel to the axis of the cut-off saw 26. This upright 62 extends inside of and through a corresponding tubular upright 63 which extends upwardly from the carrier 41. This member 63 is likewise tubular and of sufficient inside diameter to provide for the free admission of the tubular member 62, and the tubular member 62 is mounted to rotate within the tubular member 63 on the carrier by means of ball bearings 64 and 65 at the bottom and top of the carrier assembly which bearings are not only provided for rotation but to take up end and side thrust whereby the tubular member 62 and the hopper connected thereto are rotatively supported on the carrier 41. The combined hopper and car-

rier as aforesaid comprises the carriage 42. This arrangement provides for free rotation of the hopper 40 relatively to the carrier 41 and relatively to the table 3 and tracks 41 and provides for easy and convenient hand operation of the same with a minimum of frictional resistance, as hereinafter more fully described. The hopper is open at the bottom to permit the cake to rest on the table.

The tubular member 62 is shown as having a reduced cylindrical portion 67 at the top which is suitably threaded at 67'; and positioned at the said threaded top portion, to be hereinafter described in detail, is a hopper or carriage rotating handle member 68 mounted on a collar 69 which collar surrounds the cylindrical portion 67 and is keyed thereto at 70. The handle 68 and the collar 69 being held in position by a locknut or threaded collar member 71.

While the cake of ice is held by gravity in the corner of the hopper which is on the low side in both angular positions of the hopper as hereinafter described, it is also held in fixed relation to said hopper and against vibration, and lifting, and horizontal movement caused by the impact of the cake with the scoring saws and also prevented from yielding backwardly in the cut-off operation due to its impact with the high speed cut-off saw 26 by an ice engaging takeup clamp structure 73 which is part of the clamp operating assembly indicated as a whole by reference character 72. The clamp 73 is in the form of a claw foot which engages the top of the ice cake 15. In the form shown, claw foot 73 is mounted on an upright sliding shaft 74 which is provided with a rack 75 rigidly secured thereto being as shown mounted in a key slot 76. This rack has its teeth inclined on the downward side and flat on the top side. As the top of the cake recedes and is lowered by cutting of the cubes from the bottom of the cake, the clamp or clamp claw foot 73 which is on the top of the cake recedes and the shaft 74 slides downwardly and is locked in each successive position by the pawl assembly 77. This pawl assembly consists of a plurality of pawls 78 and 79, one over the other and in sliding contact. These pawls slide radially of the shaft 74 in a radial portion 80 of the handle 68 which is offset for this purpose and contains a plug 81 in which the pawls are mounted, this plug may be held in fixed relation to the said radial portion 80 of the handle in which it is located by a set screw 81', the said plug being hollow and open toward the shaft 74, carrying the rack 75. The pawls are advanced by means of springs 82 wrapped around their shanks 83. The lower pawl 79 is controlled by a button 84 mounted on its shank 83 as shown. By means of this button the pawl may be withdrawn when desired. The two pawls are interconnected by a pin 85 in the lower pawl member. The upper exposed portion of this pin engages in a short slot 86 in the upper pawl member 78, and abuts the outer end of the said slot as the pawl 79 is withdrawn beyond a certain distance. Further withdrawal of the pawl 79 likewise withdraws the pawl 78, thus enabling both the said pawls to be fully disengaged from the teeth of the rack 75 in a simultaneous manner, thereby releasing the shaft 74, and permitting it to be drawn upwardly. As the top of the cake moves downwardly due to the cut-off operations on the bottom of the cake, the top of the cake supports the claw foot 73, thus allowing the same to move

downwardly with the cake and in constant engagement therewith.

The downward or follow-up movement of the ice engaging claw foot or take up clamp 73 is effected by gravity, due particularly to the weight of the vertical shaft member 74 to which the clamp 73 is attached. As the pawls 78 and 79 are passed by the teeth of the downwardly moving rack and bar elements 75 and 74 respectively, the rack tooth engaging ends of the respective pawl members move in and out of engagement with the respectively passing rack teeth until the rack member ceases its downward movement, due to the termination of the downward movement of the ice cake when one or the other of the tooth engaging pawls 78 and 79 coming into fixed locked engagement with the respective rack tooth in registration with a pawl member locks and fixes the position of the bar 74 and clamp 73 against upward movement thereof. The purpose of using a double pawl assembly in the present instance is to split or divide the distance between the teeth whereby the points of pawl engagement therewith will be increased by a ratio of two to one for a given distance between two teeth. This arrangement also allows for the use of less teeth, whereby a heavier and more sturdy tooth may be used with a short locking throw. Thus a reliable and strong latch structure is provided to hold the cake down to its normal operating position during the scoring and cutting operations, preventing the cake from being kicked or raised upwardly by either the scoring or cut-off saws.

This clamping element is also effective in holding the cake in fixed relation and operative position in the lowermost swinging corner of the offset or extended hopper end as hereinbefore described. It will be fully understood that the above described follow-up and clamping function is constantly progressive, during normal operation of the machine until the cake is exhausted.

At the lower end of the rack 75, see Figures 10, 11, and 12 of the drawings, there is a projecting key like portion 87. In this connection it may be noted that the upper portion of the tubular upright 62 at 67 provides a bearing 88 for the sliding of the shaft 74, this bearing portion is slotted at 89 for the passage of the rack 75 and key member 87. A further function of which is to support the shaft 74 and its claw foot or clamp 73 in withdrawn or in operative position when it is desired to insert a new cake. In this respect raising the shaft 74 to the position in Figures 11 and 12 and then partially rotating the shaft 74 as shown, the key 87 is thrown out of registration with the slot 89 so that it engages the top of the cylindrical portion 67 of the upper end of the tubular member 62. This with holding of the claw foot member and shaft 74 in this manner prevents injury to the hand by dropping of the claw foot clamp member 73 and when the new cake has been inserted the shaft 73 may be rotated to bring the key member 87 into registration with the slot 89 which permits the claw foot 73 and the shaft 74 to move downwardly, the clamping member of claw foot 73 then engages the new cake and in engaged position with the cake will be locked by the pawls 78 and 79. A transverse pin 73' projecting from the top of the shaft 74 prevents the claw from contacting the table.

Referring now to Figures 4 and 9, it is of interest that a sheet metal shute is provided be-

neath the cut-off saw 26 whereby the cubes are discharged into any suitable container positioned as shown. The shute being indicated by reference character 90, the shute as shown is inclined downwardly toward the low side of the machine by an angle exceeding that of the table. It is also of interest that a deflecting plate or disc 91 is provided overlying the pulley 37 and concentric with the cut-off saw arbor, this plate 91 protects the motor bearings from the ice dust discharged by the saw and likewise prevents the cakes from being drawn in between the pulley 37 and belt 35, whereby the belt might be dislodged from the pulley. There is also, as already pointed out, an aperture 33 for discharging the ice dust from around the saw 26. An additional ice dust dispersing opening 11' is provided in the end wall of the machine at the termination of the cut-off saw guard to prevent accumulation of ice dust on the top of the said guard in this zone of operation. This opening may be provided with a chute 11 as shown to deflect the ice dust in a downward direction.

A feature of primary importance in the control of the cake is that the hopper 40 is off center as to the axis of the bearings 64 and 65 of the carrier assembly 41, see particularly for said bearings Figures 5 and 6, and 10 of the drawings. The hopper is shown as rectangular in shape as to its cross section in a plane parallel to the table and of somewhat greater dimension 100 in a direction at right angles to the gate 61 when closed and at right angles to the plane of the opening 60, its short dimension 100' being in the direction of the width of this opening 60 and in the direction of the length or radius of the gate 61 when closed. The axis of said bearings 64 and 65, while it is in the center of the short dimension, is unequally spaced as to the long dimension 100, i. e., in the position shown in Figure 5, the gate 61 and the opening 60 are nearer to the axis of bearings 64 and 65 than is the other end of the hopper at 61'. This eccentricity is of particular advantage in that the hopper 40 as it moves toward the cut off saw has its long dimension 100 disposed in the direction of reciprocation, i. e., in the direction of the length of the table and when the carriage is rotated, after the cut-off, the eccentricity of the carriage throws the long end 61' of the hopper down the incline and throws the cake off center causing the cake to be transferred from the saw 26 on to the guard 29. The hopper having been turned by means of handle 68 to the full line position of the latter in Figure 8 and to the position of the hopper in that figure, the long dimension 100 being transverse to the table, the hopper is ready for the next stroke, i. e., to be returned over the scoring saws. The cut-off saw 26 is shown slightly below the upper surface of the guard, and while the cake overhangs the saw, its weight is thus supported on the guard and removed from the saw as shown in Figure 8, and in the advance of the carriage toward the scoring saws the weight of the cake is carried by the guard until the cake passes the cut-off saw and has advanced to the supporting surface of the table 3.

In Figure 5 the low side of the machine is at the top of the figure as it is likewise in Figures 6 and 8. In rotating as above described, the hopper moves from the position Figure 5 to the position Figure 8, and the back 61' of the hopper in rotating moves or rotates or swings down the incline to the lowest position, Figure 8, and

in the next angular motion of the carriage at the other end of the stroke, the side 61' moves back to the relative position it occupies in Figure 6, so that by gravity the cake 15, even if it be smaller than the hopper or container 40, remains in contact with the sides which converge at the corner 101. Incidentally, when the cake is introduced or loaded, it is pushed into the back of the hopper into contact with the back side 61' and the side 102 being on the low side of the incline, it contacts this side and thus is seated in the corner 101. When the lock 72 is released by releasing the key 87 as before described, the claw foot 73 descends and becomes fixedly engaged with the top of the cake by means of its pointed ends as shown. Both gravity and the clamp contribute to the holding of the cake in this position. For the sides of the hopper converging at 101, any converging positioning members may be substituted.

In the operation of the machine, the hopper 40 is first moved to the position in which it is shown in Figure 6. A cake of ice 15 is then placed on the shelf 8 causing the shield 10 to swing down into the slot in the shelf as already described and the gate 61 having been thrown open, the cake is advanced into the hopper as shown. The gate being then closed, the clamp assembly 72 having been previously raised and checked in uppermost position to prevent injury to the hand, it is released and permitted to descend bringing the foot 73 into engagement with the cake. The toothed rack 75 is then engaged by the pawls 78 and 79, and the claw foot 73 is held in engagement with the top of the cake as hereinbefore described and as best shown in Figures 1 and 4. The hopper is now in the position Figure 6.

The operator normally stands at the low side of the machine and grasps the handle with his right hand. Assuming that he is right handed; in starting after the introduction of a new cake, the machine may be manipulated in any suitable manner to give two sets of scores at right angles to each other or the machine may be operated to cut the bottom of the cake which is first scored in a plurality of strips. In the loading position Figure 6, the handle extends northeasterly (i. e. in the direction of a radius of the hopper through corner 101). If it is desired to score the bottom of the cake at right angles so as to cut cubes in the first operation of the cut-off saw, it may be best to first rotate the hopper 40 by moving the handle 68 to the left turning the hopper 40 and the cake 15 to a position at right angles to the position in which it is shown in Figure 6. The hopper with the cake projecting downwardly on to the table, it being understood that the bottom of the hopper is open and spaced above the table sufficiently to clear the scoring saws as shown, may then be advanced over the scoring saws cutting a set of scores 15' in the direction relatively to the cake and hopper in which they are shown in Figure 6. The hopper and cake would then be returned over the scoring saws passing them through the same scores without turning. The hopper would be then turned moving the handle to the right and the hopper to the position Figure 6 and the hopper and cake would be advanced over the scoring saws cutting a second set of scores at right angles to the set shown in Figure 6. The handle being inclined forwardly, as best shown in Figure 1 and in fine dotted lines in Figure 8, the carriage and cake would then be advanced beyond the scoring saws and over the cut-

off saw 26, and the projecting scored portions of the cake indicated as 15" in Figure 9 would be severed as illustrated in said figure and would pass down the chute. At this time the long dimension 109 of the hopper 40 would be disposed in the direction of transverse or reciprocation which is the direction of the length of the table, the handle 68 would be in the dotted line position in Figure 8, i. e. inclined in the direction of the motion which has taken place. After the cut-off operation, the handle 68 would be moved to the left in Figure 8 to the full line position therein shown and the hopper would be rotated eccentrically swinging its long dimension 109 transversely to the direction of reciprocation and the length of the table so that the back side 61', see Figures 5 and 8, would be moved to the low point, i. e. down the incline to the low side of the machine or particularly to the side of the table that is remote from the observer in Figures 5, 6, and 8, which is the low side. This movement of the back side 61' of the hopper not only serves to retain the cake in the corner indicated by 101 in Figure 5 of the hopper, which is always on the low side of the table, but it will move the cake so that its weight rests on the low side of the guard. While the cake extends over the cut-off saw, its weight will be shifted from the cut-off saw. As the cake moves back toward the scoring saws, the handle being inclined in the direction of the scoring saws, is in position to advance the hopper and carry it and the cake therein toward the saws for the next scoring operation, and when the cake reaches the opposite or loading end of the machine as already indicated, the handle 68 will then be swung to the right, i. e., in the direction of the next motion, and the carriage and hopper with the cake therein will again be moved over the scoring saws and a second score at right angles to the one first made will be formed. The cake then being further advanced the scored portion will enter the table slot 32 which corresponds to the narrow width of the hopper, and will come in contact with the cut-off saw 26, whereby the scored cubes will be severed, as already described and as illustrated in Figure 9, and passed down the chute 90.

It is of importance in the operation described to note that stops 54 and 55 on the top of the hopper cooperate with the depending rib 52 on the carrier, the hopper being moved from one contacting position to the other in the angular motion mentioned, and that the roller 50 is so placed in relation to the track 51 that in each angular position of the hopper when it is moved over the scoring saws the roller 50 contacts the track 51 and cooperates with corresponding stop 54 and 55 and rib 52, preventing deflection of the hopper and hence of the cake from the intended path which is a direct linear path, carrying it over the scoring saws. Deflection, as already pointed out, would tend to bend or break the saws and interfere with the desired operation of the machine.

The advantages of this invention are convenience and increased utility with great simplicity and consequently small cost, and numerous advantages of construction and arrangement have been fully discussed in the preamble and in connection with the drawings.

The invention has also been described specifically and in detail so that the manner of constructing, applying, operating and using the invention may be fully understood; however, the specific terms herein are used in a descriptive

rather than in a limiting sense, the scope of the invention being defined in the claims.

What I claim as new and desire to secure by Letters Patent is:

5. 1. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the cut off saw being at one end of the path and having a guard to support the cake after the cut off, the axis of the hopper being eccentric and the said portion of the hopper having converging sides which is always on the low side of the incline being of relatively great radius as compared to other portions of the hopper.
10. 2. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging walls to position the body being cut, is always on the low side of the incline, the cut off saw being at one end of the path and having a guard to support the cake after the cut off, the axis of the hopper being eccentric and the said portion of the hopper having converging sides which is always on the low side of the incline being of relatively great radius as compared to the other portions of the hopper, and means in continuous engagement during cutting with the top of the body being cut to assist in holding said body in the position determined by said converging sides, said latter holding means having ratchet teeth and a pair of alternately operating pawls to lock the holding means in closely related positions to prevent lifting of the body by the saws.
15. 3. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the means for rotatively supporting the hopper on the carrier comprising a single rotary and thrust bearing and a shaft to which the hopper is secured rotatively supported in said bearing, said shaft being hollow and having a clamping shaft slidably mounted in said hollow, said clamping shaft having, on its lower end, a foot for en-
20. 4. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging walls to position the body being cut, is always on the low side of the incline, the cut off saw being at one end of the path and having a guard to support the cake after the cut off, the axis of the hopper being eccentric and the said portion of the hopper having converging sides which is always on the low side of the incline being of relatively great radius as compared to the other portions of the hopper, and means in continuous engagement during cutting with the top of the body being cut to assist in holding said body in the position determined by said converging sides, said latter holding means having ratchet teeth and a pair of alternately operating pawls to lock the holding means in closely related positions to prevent lifting of the body by the saws.
25. 5. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the means for rotatively supporting the hopper on the carrier comprising a single rotary and thrust bearing and a shaft to which the hopper is secured rotatively supported in said bearing, said shaft being hollow and having a clamping shaft slidably mounted in said hollow, said clamping shaft having, on its lower end, a foot for en-
30. 6. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging walls to position the body being cut, is always on the low side of the incline, the cut off saw being at one end of the path and having a guard to support the cake after the cut off, the axis of the hopper being eccentric and the said portion of the hopper having converging sides which is always on the low side of the incline being of relatively great radius as compared to the other portions of the hopper, and means in continuous engagement during cutting with the top of the body being cut to assist in holding said body in the position determined by said converging sides, said latter holding means having ratchet teeth and a pair of alternately operating pawls to lock the holding means in closely related positions to prevent lifting of the body by the saws.
35. 7. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the cut off saw being at one end of the path and having a guard to support the cake after the cut off, the axis of the hopper being eccentric and the said portion of the hopper having converging sides which is always on the low side of the incline being of relatively great radius as compared to the other portions of the hopper, and means in continuous engagement during cutting with the top of the body being cut to assist in holding said body in the position determined by said converging sides, said latter holding means having ratchet teeth and a pair of alternately operating pawls to lock the holding means in closely related positions to prevent lifting of the body by the saws.
40. 8. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the cut off saw being at one end of the path and having a guard to support the cake after the cut off, the axis of the hopper being eccentric and the said portion of the hopper having converging sides which is always on the low side of the incline being of relatively great radius as compared to the other portions of the hopper, and means in continuous engagement during cutting with the top of the body being cut to assist in holding said body in the position determined by said converging sides, said latter holding means having ratchet teeth and a pair of alternately operating pawls to lock the holding means in closely related positions to prevent lifting of the body by the saws.
45. 9. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the cut off saw being at one end of the path and having a guard to support the cake after the cut off, the axis of the hopper being eccentric and the said portion of the hopper having converging sides which is always on the low side of the incline being of relatively great radius as compared to the other portions of the hopper, and means in continuous engagement during cutting with the top of the body being cut to assist in holding said body in the position determined by said converging sides, said latter holding means having ratchet teeth and a pair of alternately operating pawls to lock the holding means in closely related positions to prevent lifting of the body by the saws.
50. 10. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the cut off saw being at one end of the path and having a guard to support the cake after the cut off, the axis of the hopper being eccentric and the said portion of the hopper having converging sides which is always on the low side of the incline being of relatively great radius as compared to the other portions of the hopper, and means in continuous engagement during cutting with the top of the body being cut to assist in holding said body in the position determined by said converging sides, said latter holding means having ratchet teeth and a pair of alternately operating pawls to lock the holding means in closely related positions to prevent lifting of the body by the saws.
55. 11. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the cut off saw being at one end of the path and having a guard to support the cake after the cut off, the axis of the hopper being eccentric and the said portion of the hopper having converging sides which is always on the low side of the incline being of relatively great radius as compared to the other portions of the hopper, and means in continuous engagement during cutting with the top of the body being cut to assist in holding said body in the position determined by said converging sides, said latter holding means having ratchet teeth and a pair of alternately operating pawls to lock the holding means in closely related positions to prevent lifting of the body by the saws.
60. 12. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the cut off saw being at one end of the path and having a guard to support the cake after the cut off, the axis of the hopper being eccentric and the said portion of the hopper having converging sides which is always on the low side of the incline being of relatively great radius as compared to the other portions of the hopper, and means in continuous engagement during cutting with the top of the body being cut to assist in holding said body in the position determined by said converging sides, said latter holding means having ratchet teeth and a pair of alternately operating pawls to lock the holding means in closely related positions to prevent lifting of the body by the saws.
65. 13. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the means for rotatively supporting the hopper on the carrier comprising a single rotary and thrust bearing and a shaft to which the hopper is secured rotatively supported in said bearing, said shaft being hollow and having a clamping shaft slidably mounted in said hollow, said clamping shaft having, on its lower end, a foot for en-
70. 14. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the means for rotatively supporting the hopper on the carrier comprising a single rotary and thrust bearing and a shaft to which the hopper is secured rotatively supported in said bearing, said shaft being hollow and having a clamping shaft slidably mounted in said hollow, said clamping shaft having, on its lower end, a foot for en-
75. 15. In a machine for cutting bodies of material into uniform blocks, a carrier mounted to reciprocate on a single rectilinear path, a hopper rotatively mounted thereon and depending therefrom, a table beneath the hopper and substantially parallel to said path, the axis of the hopper being normal to the table and the table being inclined transversely to the path of reciprocation, a cut off saw and scoring saws in operative relation to said path and means for limiting the turning of the hopper to positions in which one portion of the hopper, having converging sides to position the body being cut, is always on the low side of the incline, the means for rotatively supporting the hopper on the carrier comprising a single rotary and thrust bearing and a shaft to which the hopper is secured rotatively supported in said bearing, said shaft being hollow and having a clamping shaft slidably mounted in said hollow, said clamping shaft having, on its lower end, a foot for en-

gaging the top of the body being cut to hold the latter in cutting position.

4. In a machine for cutting bodies of ice or other materials into relatively small uniform blocks, a carrier mounted for reciprocation on a predetermined path, a hopper rotatively mounted on the carrier and open at the bottom, a table spaced downwardly from the hopper to support bodies in the said hopper, the table being beneath the said hopper and substantially parallel to said path, a cut off saw in the path of the bodies in the hopper, scoring saws adjacent said path and parallel to the same and projecting through the plane of the table into said path, means for reciprocating the carrier and hopper along said path and turning the hopper through equal and opposite angles at the ends of the path, and means moving with the carrier for holding the bodies to be cut in said hopper preventing lateral and upward motion of said body relatively to said hopper, comprising a shaft extending downwardly into the hopper in line with the axis of said hopper, the same being mounted to slide freely in the direction of said axis and having an engaging foot adapted to engage and to be supported on the top of the body being cut and having automatic locking means for holding the shaft against upward motion in each position of rest of said foot as the top of the body recedes downwardly in correspondence with the consumption of the body by the operation of said saws.

5. In a machine for cutting bodies of ice or other materials into relatively small uniform blocks, a carrier mounted for reciprocation on a predetermined path, a hopper rotatively mounted on the carrier and open at the bottom, a table spaced downwardly from the hopper to support bodies in the said hopper, the table being beneath the said hopper and substantially parallel to said path and the axis of rotation of the hopper being normal to said table and upwardly disposed, a cut off saw in the path of the bodies in the hopper, scoring saws adjacent said path and projecting through the plane of the table into said path, means for reciprocating the carrier and the hopper along said path and turning the hopper at the ends of the path, and means for holding the bodies to be cut in said hopper preventing lateral and upward motion of said bodies relatively to said hopper, said holding means being mounted to slide freely in a direction normal to the table and having a foot for engaging the top of the body being cut and means for applying continuous downward pressure to said foot causing it to move downwardly and to continue in engagement with the top of said body as said top recedes downwardly in correspondence with the consumption of said body by said saws, and automatic locking means for holding said engaging means against upward motion, in a series of closely related positions arranged in said direction normal to the table.

6. In a machine for cutting blocks from bodies of ice or similar material, a carrier mounted to reciprocate on a predetermined rectilinear path, a hopper mounted on said carrier to rotate relatively thereto and open at the bottom, a table beneath said hopper and parallel to said path, said table having a supporting surface for the body of the material in said hopper which surface is inclined to the horizontal in a direction transverse to said path, a gang of scoring saws projecting through the plane of the table

into the path of a body carried by the hopper resting on the table, a cut off saw parallel to the table and spaced above the same the desired height of the blocks to be cut and means for reciprocating the hopper and turning it about an upwardly disposed axis normal to the table at each end of its path, a saw guard adjacent the cut off saw and slightly above the same, the guard extending along the low side of said saw, the hopper being eccentrically pivoted, means for controlling the turning of the hopper and limiting said turning to positions in which a portion of the hopper of the greatest radius is on the low side of the inclined table and below the hopper axis, said portion having converging members for positioning the cake, and a handle for operating the hopper and carrier, the handle being connected to the hopper to turn the same projecting in the general direction of a radius of the hopper at said portion of greatest radius.

7. In a machine for cutting blocks from bodies of ice or similar material, a carrier mounted to reciprocate on a predetermined rectilinear path, a hopper mounted on said carrier to rotate relatively thereto and open at the bottom, a table beneath said hopper and parallel to said path which is substantially horizontal, said table having a supporting surface for the body of the material which is inclined to the horizontal in a direction transverse of said path, the axis of the hopper being normal to the said surface, a gang of scoring saws spaced in accordance with the desired dimensions of the blocks projecting through the plane of the table into the path of a body carried by the hopper, a cut off saw in the path of the bodies in said hopper at one end of said path and parallel to the table and spaced above the same the desired height of the blocks to be cut, and means for reciprocating the hopper and turning it at each end of its path, the hopper being eccentrically pivoted and having portions of different radii and stops limiting the arc of turning of the hopper to positions in which a portion of the hopper of greatest radius, and having converging lateral members to position the cake, is over the low side of the inclined table, whereby the body being cut is given a tendency to remain in one position in the hopper and in contact with the projecting portion of the hopper of greatest radius without regard to the size of the body.

8. In a machine for cutting blocks from bodies of ice or similar material, a carrier mounted to reciprocate on a predetermined rectilinear path, a hopper mounted on said carrier to rotate relatively thereto and open at the bottom, a table beneath said hopper and parallel to said path which is substantially horizontal, said table having a supporting surface for the bodies of material being cut which surface is inclined to the horizontal in a direction transverse of said path, the axis of the hopper being secured to the table, a gang of scoring saws spaced in accordance with the desired dimensions of the blocks projecting through the plane of the table into the path of a body carried by the hopper and resting on the table, a cut off saw in the path of the bodies in said hopper at one end of said path the same being parallel to the table and spaced above the same by the desired height of the blocks and means for reciprocating the hopper and turning it at each end of its path, the hopper being eccentrically pivoted and having portions of different radii, and stops limiting the

arc of turning of the hopper to positions in which a portion of the hopper of greatest radius is over the low side of the inclined table, said portion having converging lateral members for positioning said body being cut, whereby the body being cut is given a tendency to remain in one position in the hopper and in contact with the said positioning members without regard to the size of the body, and other means bearing downwardly continuously during the cutting operation on the body being cut to hold it in said position, and automatic locking means continuously operative during cutting to prevent yielding of said holding means.

9. In a machine for cutting bodies of material into relatively small blocks, a carrier mounted to reciprocate on a predetermined rectilinear path, a hopper rotatively mounted on the carrier and open at the bottom, a table beneath the hopper and adapted to support a body to be cut carried in the hopper, the table being substantially parallel to said path and being inclined from the horizontal in a direction transverse to said path, scoring saws intermediate of said path projecting upwardly through the plane of said table into the path of the body of said hopper, a cut off saw at one end of said path and substantially parallel to the plane of the table and spaced above the table a distance corresponding to the height of the block to be cut, a guard for the cut off saw extending slightly above the same and comprising a support for the body being cut at the side of the cut off saw adjacent the low side of the table, means for reciprocating the carrier along said path and turning the hopper about its axis of rotation which is normal to the table at the ends of said path, the hopper being eccentrically pivoted providing a portion of relatively long radius adapted to hold and position the body to be cut and stops limiting the turning of the hopper to positions in which the portion of the hopper having the long radius is maintained over the low side of the table, whereby the body of the material being cut is removed from the cut off saw by the turning operation immediately after the cut off, and transferred to the guard support.

10. In a machine for cutting bodies of material into relatively small blocks, a carrier mounted to reciprocate on a predetermined path, a hopper rotatively mounted on the carrier and open at the bottom, a table beneath the hopper and adapted to support a body to be cut carried in the hopper, the table being substantially parallel to said path and being inclined to the horizontal in a direction transverse to said path and the axis of rotation being substantially normal to the table, scoring saws intermediate of said path projecting upwardly through the plane of said table into the path of a body in said hopper, a cut off saw at one end of said path substantially parallel to the table spaced above the table a distance corresponding to the height of the block to be cut, a support for the body being cut at the side of the cut off saw corresponding to the low side of the table, means for reciprocating the carrier along said path and turning the hopper through opposite angles at each end of said path about its axis of rotation which is normal to the table, the hopper being eccentrically pivoted providing a portion of the hopper of relatively long radius which long radius portion is adapted to hold and position the body to be cut and stops whereby the angle of turning of the hopper is limited to posi-

tions in which a portion of the hopper having the longest radius is maintained over the low side of the table said long radius of the low side of the hopper and the angle of turning between said stops being sufficient to provide for the transfer of the body of the material being cut which is held by gravity in the long radius portion of the hopper, from the cut off saw to said support by the turning operation immediately after the cut off, and an additional means operating intermediate of the path to prevent turning of the hopper while it is passing the cut off saw.

11. In a machine for cutting blocks from bodies of ice and similar materials, a carrier, means for reciprocating the carrier on a predetermined path, a hopper mounted on the carrier to turn through predetermined angles about an upwardly extending axis, the hopper being open at the bottom, a table beneath the hopper and adapted to support a body carried therein, the table being substantially parallel to said path and inclined to the horizontal in a direction transverse to said path, scoring saws projecting through the plane of the table into the path of a body in the hopper, a cut off saw also in the path of the body in the hopper and substantially adjacent to one end of said path, the cross section of the hopper parallel to the table being oblong, said axis being substantially in the center of the short dimension and off center as to the long dimension of said cross section of the hopper said cross section thus having two corners near the axis and two corners relatively remote from said axis, and stopping means for limiting the rotation of the hopper to positions in which one of said remote corners is on the low side of the incline.

12. In a machine for cutting blocks from bodies of ice and similar materials, a carrier, means for reciprocating the carrier on a single predetermined path, a hopper mounted on the carrier to rotate about an upwardly extending axis and open at the bottom, a table beneath the hopper and adapted to support a body carried therein, the table being substantially parallel to said path said axis being inclined to the vertical in a direction transverse to said path, scoring saws projecting upwardly into the path of the body in the hopper, a cut off saw at right angles to said axis and inclined to the horizontal and in the path of the body in the hopper and substantially adjacent to one end of said path, a support for the body being cut, the support being adjacent the low side of the cut-off saw and slightly above the plane of said saw and the cross section of the hopper parallel to the cut-off saw being oblong, said axis being substantially in the center of the short dimension and off center as to the long dimension of said cross section, the hopper thus having two corners near its axis and two corners relatively remote from said axis, and stopping means for limiting the rotations of the hopper to positions in all of which one of said remote corners is on the low side of the incline, and a handle for said hopper whereby it is reciprocated, and turned at each end of its path, said handle projecting in the general direction of the diagonal at said low corner the long dimension of the said hopper section being parallel to the path as the hopper approaches the cut-off saw, the turning of the hopper after the cut-off serving to transfer the weight of the body from the cut-off saw to the support.
